STORAGE RACK FOR A SET OF MACHINE TOOLS

Robert F. Anderson, 3613 13th St.,
Menominee, Mich. 49858

Filed Dec. 11, 1970, Ser. No. 26,417

Term of patent 14 years

Int. Cl. D6—04

U.S. Cl. D6—125

The figure is a perspective view of the storage rack for a set of machine tools, embodying my new design.

I claim:

The ornamental design for a storage rack for a set of machine tools, as shown.
